MEASURING CUP

Hester A. Pittman, Lomita, Calif.
(2558 Gundry Ave., Long Beach, Calif. 90806)

Filed Oct. 6, 1965, Ser. No. 87,344

Term of patent 14 years

(Cl. D44—29)

FIGURE 1 is a perspective view of a measuring cup embodying my new design;

FIGURE 2 is a bottom plan view of the measuring cup;

FIGURE 3 is a sectional view taken along line 3—3 of FIGURE 1;

FIGURE 4 is a sectional view taken along line 4—4 of FIGURE 1; and

FIGURE 5 is a sectional view taken along line 5—5 of FIGURE 1.

The essential features of the design are shown in full lines.

I claim:

The ornamental design for a measuring cup, substantially as shown and described.
